UNITED STATES PATENT OFFICE.

JAMES W. RAMSDELL, OF HIGHLAND PARK, MICHIGAN.

DRINKING FOUNTAIN.

1,278,999.

Specification of Letters Patent Patented Sept. 17, 1918.

Application filed January 14, 1918. Serial No. 211,804.

To all whom it may concern:

Be it known that I, JAMES W. RAMSDELL, a citizen of the United States, residing at Highland Park, in the county of Wayne and State of Michigan, have invented certain new and useful Improvements in Drinking-Fountains, of which the following is a specification.

This invention relates to drinking fountains and has for its object to provide a drinking fountain which will be free from unsanitary conditions characteristic of some of the drinking fountains or bubble cups in common use. It has been demonstrated by investigations made by competent persons. (See *Public Health Reports*, May 11, 1917. Reprint No. 397, U. S. Public Health Service) that bubble cups of the unprotected type, to which the mouth of the drinker is applied, are conducive to the dissemination of injurious bacteria, due to the contact of the lips of the drinker or to the contamination of waste water in the bowl. These objections are avoided by the present invention in which the water is caused to flow from a protected jet orifice in a stream which is out of contact with the walls of the bowl and to which the mouth of the drinker is applied out of contact with the jet orifice and with the other parts of the device.

A further object of the invention is to provide an improved structure in which the waste water cannot come in contact with the orifice, and in which the stream is sparkling and aerated and convenient for drinking purposes.

Further objects of the invention will be apparent from the following description and the accompanying drawings:

10 In the drawings, Figure 1 is a top plan view of the bowl. Fig. 2 is a central vertical section. Fig. 3 shows details of various shapes of the jet orifice for purposes to be hereinafter referred to.

15 Referring specifically to the drawings, 6 indicates a bowl or cup. This may be made of metal or pottery, and is of sufficient depth and size to surround the stream and take care of the waste water which escapes through the waste trap 7 at the bottom. This trap is of novel construction and forms the subject of a separate application for patent.

20 In the side wall of the bowl an opening 8 is produced directed inwardly and upwardly, and on the inside of the bowl,

around this opening, there is a rim 9 which is so shaped on the upper side at least that any drip or splash against the side of the bowl will be directed away from the opening, so that it will run down the inside of the bowl instead of escaping through the opening. This is effected by beading the rim, to form a channel 10 around the same. Above this opening, the inner wall of the 25 bowl is provided with a shield or projection 11 which overhangs the opening and prevents the drinker from applying his mouth thereto.

The water is supplied through the pipe 12, 30 which may be controlled by a push valve 13 and this pipe leads to a head 14 which is spaced from the exterior of the bowl, the head being united to the pipe by a rubber ring 15, a slip ring 16 and a lock nut 17, to 35 form a water tight joint. The head is provided on the side adjacent to the bowl with a nozzle 18 directed upwardly and inwardly in line with the opening 8, and above the nozzle the head has a chamber 19 in which 40 air is trapped to prevent water hammer and insure a regular flow.

The size of the nozzle 18 is such that the stream of water discharged therefrom is smaller than the opening 8, so that when water is discharged through the nozzle air is entrained therewith as it passes through the opening 8. The form and construction of the parts are such that the stream of water describes a parabolic curve in the bowl, 50 with its crest just above the top of the bowl and substantially at the axis thereof. The mouth of the drinker is applied to the stream at this crest. In order to give a sparkling stream the form of the jet may be varied to 55 break up and aerate the same. Several of these forms are illustrated in Fig. 3. Thus the orifice of the nozzle may be in the shape of an oval, a cross, or a parallelogram, which will have the effect of entraining air at the 60 nozzle and at the opening 8 to give a sparkling stream of appetizing appearance.

As the stream passes through the opening 8 it clears the sides thereof and avoids any danger of contamination from matter collected on or in the bowl. The nozzle is also out of contact with the bowl and there is no danger of germs spreading from the bowl to the nozzle. The nozzle is protected from the waste water, and should any splash or 65 waste escape through the opening 8 it will flow down the side of the bowl in the space

between the opening and the nozzle. The supply pipe and head can also be readily assembled or attached without disconnecting the bowl.

5 I claim:

1. A drinking fountain comprising a bowl having an opening in the wall thereof, and a supply pipe with a nozzle spaced from said opening and arranged to discharge a jet 10 through said opening and into the bowl, the opening being only slightly larger than the jet, whereby air is entrained in the jet by an injector action, as the jet flows through the opening.
- 15 2. A drinking fountain comprising a bowl

having an opening in its side wall, and an external supply pipe and nozzle, the nozzle being directed toward said opening, to discharge a jet therethrough into the bowl, and being spaced from the wall of said opening, 20 said wall converging toward the jet, and being sufficiently close to the jet to cause air to be entrained therewith.

In testimony whereof, I do affix my signature in presence of two witnesses.

JAMES W. RAMSDELL.

Witnesses:

R. E. Scott,
GERALD E. BUCKLEY.
